UNITED STATES PATENT OFFICE

163,684

PICTURE MAT

Jess R. Forman, Kansas City, Mo.

Application January 15, 1951, Serial No. 13,808

Term of patent 3½ years

(Cl. D29—20)

To all whom it may concern:

Be it known that I, Jess R. Forman, a citizen of the United States, residing at Kansas City, in the county of Jackson and State of Missouri, have invented a new, original, and ornamental Design for a Picture Mat, of which the following is a specification, reference being had to the accompanying drawing, forming a part thereof.

Fig. 1 is a front elevational view of the picture mat, showing my design.

Fig. 2 is a sectional view taken on line II—II of Fig. 1.

I claim:

The ornamental design for a picture mat, as shown.

JESS R. FORMAN.
